KNIFE RACK

Jack Eisner, Kew Garden Hills, N. Y.

Application May 16, 1957, Serial No. 46,253

Term of patent 14 years

(Cl. D44—29)

FIG. 1

FIG. 2

Figure 1 is a front elevational view of a knife rack showing my new design.

Figure 2 is a side view thereof.

I claim:

The ornamental design of a knife rack, as shown.
